H. O. Huntington

BY C. B. Birkenmeier.
ATTORNEY

UNITED STATES PATENT OFFICE

HAROLD O. HUNTINGTON, OF SEATTLE, WASHINGTON, ASSIGNOR TO HENRY O. BENEDICT, OF SEATTLE, WASHINGTON

DUST GUN

Application filed June 25, 1928. Serial No. 287,990.

This invention relates generally to the art of applying insecticides, and particularly to a special form of gun where dust can be applied in a convenient manner.

5 The main object of this invention is to provide an exceedingly simple and efficient form of dust gun whereby powdered insecticide may be applied in remote and inaccessible places by a very simple operation.

10 The second object is to so construct the gun that it can also be used as a cheap and convenient container in which insecticide can be sold.

15 The third object is to provide a special form of valve which will be easy to construct and infallible in operation.

These, and other objects, will become more apparent from the specification following as illustrated in the accompanying 20 drawing, in which:

Figure 1 is a longitudinal section through the device showing it extended and taking air in at its inlet end. Figure 2 is a similar view showing the gun in a closing position with dust being ejected from its discharge end. Figure 3 is a perspective view of the inner valve disk. Figure 4 is an elevation of the inner valve disk. Figure 5 is a section taken along the line 5-5 in Figure 4. Figure 6 is a section taken along the line 6-6 in Figure 1. Figure 7 is a section taken along the line 7-7 in Figure 1. Figure 8 is an elevation showing the shape of the discharge nozzle.

35 Similar numbers of reference refer to similar parts throughout the several views.

Referring in detail to the drawings, the gun consists of two principal parts, the first being the container and the second the air injecting tube. The container consists of a cardboard tube 10 in one end of which is placed a cap 11 provided with a unique form of check valve 12 which is preferably made of sheet rubber and is cemented to the cap 40 11 on three sides leaving the side 13 in contact with the cardboard, but not attached thereto. The opening 14 over which the rubber 12 is placed is preferably flanged toward the rubber sheet 12 for the purpose of 45 making a better contact therewith.

At the other end of the tube 10 is mounted a closure 15 which is, in reality, mounted upon a separate tube 16, which, in turn, is secured to the tube 10. In the closure 15 is also mounted a dust discharging nozzle 17 whose tip 18 is flattened to form a better shape for the outlet. The nozzle 17 is also provided with perforations 19 on its under side and a portion 20 of the nozzle 17 is turned to form an obstruction within the nozzle 17. The nozzle 17 is cemented in the inwardly flanged opening 21.

The air injecting tube consists of a tubular cardboard member 22 similar in diameter to the tube 16, but slidably mounted on the tube 10. Over the end of the tube 22 is secured a cover 23 on the middle portion of which is formed a flap valve 24, preferably of a fairly heavy piece of rubber which merely hinges on the fastening staple 25; whereas the member 12, which is also rubber, must actually stretch before air can pass through the opening 14.

Powder 26 is placed in the tube 10 either through one end or the other, whichever may be most convenient, and the members 11 and 15 securely fastened. Any extending action of the air injection tube 22 causes air to pass inwardly through the opening 27, and a movement in the opposite direction causes the flap valve 24 to close and the air to be compressed within the tube 22 between the ends 11 and 23 until the pressure is sufficient to unseat the member 12 and allow air to pass through the opening 14 and to blow upwardly through the powder 26 thereby agitating same and causing a dust-laden air to pass through the opening 19 and to be discharged from the tip 18.

It will be noted that while the opening 27 is in the center of the member 23, the opening 14 is at one side of the tube 10, while the discharge nozzle 17 is at the opposite side thereof. In operation the discharge nozzle is always held uppermost, which naturally causes the opening 14 to be lowermost and insures a thorough agitation of the insecticide.

I am aware that many forms of dust spraying devices have been constructed in the

past; it is therefore not my intention to cover such devices broadly, but I do intend to cover all such forms and modifications thereof as fall fairly within the appended claims.

I claim:

5. 1. A container for insecticides consisting of a tubular member having a closure at each end thereof, one of said closures having a spray nozzle mounted at one side thereof parallel to the axis of the tube, said spray nozzle consisting of a cylindrical member having a flattened tube extending upwardly through said closure, the inner portion of said nozzle having perforations formed therein, a flanged opening formed in the opposite side of the opposite closure member having its flange extending inwardly, a sheet rubber secured along three sides over said opening the fourth side lying along the outer portion of the container, and means for forcing air through said flanged opening into the interior of said container.
10. 2. In a dust gun the combination of a tubular paper container having a cylindrical cap mounted over one end thereof, one end of said cap being closed and having a round opening formed along one side thereof, a tubular nozzle mounted in said opening one end of which projects into said gun and is provided with perforations and the other end of which projects out of said gun and is flattened, a closure for the opposite end of said tube consisting of a flanged disk adapted to fit inside of said tube end, said flanged disk having a flanged opening formed at one side thereof on the opposite side of said tube from which lies said nozzle, said flange extending inwardly into said container, a check valve for said flanged opening consisting of a piece of flexible rubber secured over said opening on the inside of said disk along three sides of said sheet of rubber leaving one unsecured side toward the rim of said disk, and an air injecting means consisting of a slid able tubular cap member mounted on the end of said container opposite its nozzle, said cap having a closed head provided with a flanged opening adapted to open under external pressure and to close under internal pressure.
15. 3. A nozzle for spray guns consisting of a tubular cardboard member having one end thereof flattened to form a tip and having one side of the tubular portion perforated, a portion of said perforated side turning inwardly to form a closure for the inlet end of the nozzle, said closure portion having inlet apertures formed therein, a portion of said tubular cardboard member extending beyond said inlet end to form a shield therefor.

60 HAROLD O. HUNTINGTON.
